UNITED STATES PATENT OFFICE.

HARRY FOTHERGILL, OF WESTMINSTER, LONDON, ENGLAND.

AUTOMATIC CONTROL OF STEAM-CONDENSING PLANTS.

1,392,003.

Specification of Letters Patent. Patented Sept. 27, 1921.

Application filed August 8, 1919. Serial No. 316,186.

To all whom it may concern:

Be it known that I, HARRY FOTHERGILL, a subject of the King of Great Britain, residing at 3 Central Buildings, Westminster, 5 London, England, have invented Improvements in and Connected with the Automatic Control of Steam-Condensing Plants, of which the following is a specification.

This invention relates to improvements in 10 and connected with the automatic control of steam condensing plants in which a valve operated automatically by the steam pressure available as a consequence of the operation of the main engine is employed to control the admission of cooling medium to the condenser.

In the case of reciprocating engines for 15 instance operating in conjunction with steam condensers of that general character where a steam jet or jets is or are employed for extracting aerated vapor from the condenser and delivering it to a receiver or secondary condenser wherein it is condensed and from which the air is extracted by 20 means of an air pump driven from the main engines, it is obviously undesirable for the steam jet or jets to continue operating when the main engines—and as a consequence the air pump—are not running. Nor is it desirable 25 in such a case to continue the circulation of condensing water to the condensing receiver.

In the case of steam turbines the circumstances are somewhat different since the air 30 withdrawing and discharging apparatus is usually operated continuously and independently of the turbine, but here again it is necessary to control the temperature by bypassing a quantity of water from the tank 35 or condensing receiver into which the steam jet or jets discharge into the main condenser.

Moreover, in such plants, condensate is usually withdrawn from the main condenser by a rotary pump, and in order to provide 40 for the satisfactory working of such pumps it is desirable to keep them continuously supplied with water, a desideratum which can be attained with apparatus in accordance with my invention.

The object of my invention is to provide 45 an improved arrangement constituting a steam condensing plant wherein the temperature of the auxiliary condenser is controlled by automatically bypassing a quantity of water from the tank or condensing

receiver into which the steam jet or jets discharge, into the main condenser.

A steam condensing plant according to this invention comprises a main condenser, an auxiliary condensing device into which 60 condensate from the main condenser is discharged, a pipe leading from the auxiliary condensing device to the main condenser, and an automatic valve in said pipe controlled by steam or other pressure available 65 only when the engines are running for controlling the flow of water in said pipe.

In the accompanying drawings I have illustrated embodiments of my invention diagrammatically, Figure 1 being a diagram 70 of an apparatus suitable for use with reciprocating engines,

Fig. 2 is a diagram of one form of device for application to steam turbines,

Fig. 3 is an enlarged view of the valve 75 employed in this case,

Fig. 4 is a similar view of a modified apparatus,

Fig. 5 is an enlarged view of the valve employed in this modification and Figs. 6 and 80 7 are similarly views of a further modified apparatus and the valve employed therein respectively.

Referring to these drawings and particularly to Fig. 1 which shows one form of my 85 invention capable of application to the main reciprocating engines of a steamship in which aerated vapor is withdrawn from the condenser by a steam jet which discharges into a condensing receiver from which the 90 contents are withdrawn by an air pump driven from the main engines, the numeral 1 designates a piston adapted to operate a valve 2 controlling the supply of steam to the steam jet ejector and a valve 3 95 controlling the supply of water to a condensing receiver into which the steam jet ejector discharges in accordance with known practice. These valves are normally closed by springs 4 and 5 and a lost motion connection 6 is provided between the two valves so that in operation the valve 3 will be opened slightly in advance of the valve 2 so as to insure the supply of condensing water to the condensing receiver being available to condense the steam delivered to the receiver by the steam jet. A pipe 7 controlled if desirable by a cock 8 leads from some part of the main engine where pressure fluid occurs only when the engines are 105 110

running. For instance, in a triple expansion steam engine this pipe 7 may conveniently be connected to the intermediate receiver. The exhaust or other steam supply for operating the steam jet enters the casing of the valve 2 as indicated by the arrow 9 and the steam passes to the steam jet as indicated by the arrow 10 and the water from the air pump discharge, which water is usually condensate from the main condenser passes into the valve casing as indicated by the arrow 11 and passes out to the condensing receiver as indicated by the arrow 12.

15 In operation when the main engines are running, steam from the intermediate receiver or other suitable pressure supply passes to the space 13 above the piston 1, assuming of course, that the valve 8 is in open 20 position and the steam pressure acting on this piston 1 overcomes the force of the springs 4 and 5 and this causes the valve 2 and 3 to open, the lost motion connection 6 insuring that the valve 3 opens slightly in 25 advance of the valve 2 as before indicated. If however, the main engine is stopped and the steam pressure falls below a certain limit the springs 4 and 5 operate to close the valves 2 and 3 and this automatically 30 cuts off the supply of steam to the steam jet ejector and the supply of water to the condensing receiver.

In Figs. 2 and 3 I have illustrated one form which my invention may take as applied to the control of a by pass valve between the main condenser and an auxiliary condensing device which in this example is shown as a tank. Referring to these figures, the main condenser is indicated at 14 and 40 aerated vapor is withdrawn from this condenser by the steam jet ejector 15 and discharged through the perforated pipe 16 into a tank 17 to which the condensate is also delivered by the pump 18, by way of the pipe 45 17^a, the non-return valve 19 preventing any back flow from this tank 17. A pipe 20 leads from the tank 17 to the condenser 14 and the automatic valve illustrated in detail in Fig. 3 controls the flow from the tank 17 50 to the condenser 1. This valve comprises a diaphragm 21 loaded by a spring 22 and connected to operate the by pass valve proper 23. A pipe 24 leads from the turbine casing 26 or from elsewhere where the pressure varies with variations in load on the turbines, such for instance as the steam supply between the throttle valve and the turbines, to the chamber 25 above the diaphragm and another pipe 27 leads from a 55 position between the delivery side of pump 18 and the non-return valve 19 to the chamber 28 beneath the diaphragm 21. This diaphragm 21 is so loaded by the spring 22 that when the turbine is starting up or running under light load, the valve is held open

60 by the spring assisted by the pressure of the water in the discharge pipe of the pump 18 and water from the tank 17 is delivered to the condenser 14 wherein it is cooled. At half load or some other predetermined load 70 the steam pressure from the turbine casing 26 acting on the diaphragm 21 overcomes the spring and the valve 23 closes, the condensate from the condenser at this predetermined load being sufficient to condense 75 the steam and aerated vapor delivered to the tank 27 by the steam jet ejector 15. If for any reason the condensate pump 18 fails the non-return valve 19 will shut and a vacuum, consequent upon the vacuum in the condenser 14, will be produced in the chamber 80 28 beneath the diaphragm and the valve 23 will close, thus preventing flooding of the condenser.

The arrangement shown in Figs. 4 and 5 85 differs somewhat from that shown in Figs. 2 and 3. In this case the first steam jet ejector 15 delivers aerated vapor to a condensing receiver 29 and a second steam jet ejector 30 discharges into the tank 17, from 90 which water is discharged to the condensing receiver 29 by way of the pipe 31 which may be provided with a valve. The hot water from the condensing receiver passes by way of the looped pipe 32 to the pipe 33 95 which is connected at one end to the condenser 14 and at the other end to the suction side of the condensate pump 18. In this case the diaphragm 21 is so loaded by the spring 22 that the valve 23 is held closed 100 when the turbine is starting and until half or other predetermined load is reached and the hot water from the condensing receiver 29 passes into the main condenser 14 and is cooled. When this predetermined load occurs, however, the pressure from the turbine casing 26, acting on the diaphragm 21 overcomes the spring and the valve opens, thus allowing the hot water from the condensing receiver 29 to pass to the suction 110 side of the condensate pump 18 and be utilized for heating up the condensate from the main condenser.

A further modified arrangement is shown in Figs. 6 and 7. In this case the steam jet ejector 15 is in series with a water jet ejector 34 and discharges into the tank 17, the water jet ejector being supplied with water from the tank 17 by means of the pump 35, condensate from the main condenser 14 being delivered to the tank 17 by the pump 18 as before. A pipe 36 leads from the pipe 37, leading to the water operated ejector, to the main condenser and here again the loading of the diaphragm 21 is such as to 120 insure the automatic valve 23 being closed at starting. At starting and until this predetermined load is reached water under pressure from the pump 35, passes through 125 the passage 35^a, acting on the underside of 130

- the diaphragm 21, opens the valve 23 thus allowing water to be returned by way of the pipe 36 to the condenser 14. When the predetermined load on the turbine is reached, however, the stream pressure from the turbine casing 26 assists the spring to overcome the water pressure and the valve 23 closes. If from any cause the pumps should fail it is obvious that the water pressure acting on the diaphragm 21 will fail and the valve will close thus preventing flooding of the condenser.
- The piston, diaphragm or the like may be so loaded that as soon as the main engines are started, and even a small pressure applied to it, the piston, diaphragm or the like will be caused to move, and the valve or valves or other element or elements operated. Or the piston diaphragm or the like may be so loaded that the movements of the valve or valves or other element or elements varies with increases or decreases of pressure, and consequently of the load on the main engine.
- In cases where two or more valves are operated in accordance with my invention, said valves may be caused to open consecutively, a space of time elapsing between the opening of one valve and the opening of the next in series.
- The piston or diaphragm, and the valve, may be of any convenient type, and although I have referred particularly to a turbine, it will be understood that the invention is applicable to the condensing plant of reciprocating steam engines.
- What I claim and desire to secure by Letters Patent is:—
1. A steam condensing plant comprising a main condenser, an auxiliary condensing device into which condensate from the main condenser is discharged, a pipe leading from the auxiliary condensing device to the main condenser and an automatic valve in said pipe controlled by steam or other pressure available only when the engines are running for controlling the flow of water in said pipe.
  2. A steam condensing plant as set forth in claim 1 having automatic valves comprising a piston or diaphragm held in position by spring or other load until the steam pressure in an engine receiver or turbine casing reaches a predetermined value.
  3. A steam condensing plant as set forth in claim 1 wherein the operation of the automatic valve is also dependent on the effective working of a pump or pumps.
  4. A steam condensing plant comprising a condenser, a tank, a steam jet ejector discharging from said condenser into said tank, a pump discharging condensate from said condenser to said tank, a return pipe leading from said tank to said condenser, an automatic valve in said pipe adapted to be held open by a spring until the engine or turbine attains a predetermined steam load and means for insuring closure of said valve when said load is attained and also in the event of failure of the condensate pump substantially as specified.

Signed at London, England, this 22 July, 1919.

H. FOTHERGILL.
